UNITED STATES PATENT OFFICE.

ALBERT KOCH, OF ITHACA, NEW YORK.

METAL-EXTRACTING MACHINE.

Application filed September 17, 1923. Serial No. 663,187.

To all whom it may concern:

Be it known that I, ALBERT KOCH, a citizen of the United States of America, and a resident of Ithaca, county of Tompkins, 5 State of New York, have invented certain new and useful Improvements in Metal-Extracting Machines, of which the following is a specification.

This invention relates to certain improvements in machines for and methods of extracting metals; and the nature and objects of the invention will be readily recognized and understood by those skilled in the arts involved in the light of the following explanation and detailed description of the accompanying drawing illustrating what I at present consider to be the preferred embodiment or mechanical expression of the invention from among various other forms, 15 arrangements, combinations and constructions of which the invention is capable within the spirit and scope thereof.

The invention deals with and is applicable generally to the extraction and separation of metals from metal bearing earths; but is more particularly directed to the extraction and separation of precious metals, such as gold, when found in the free state mixed with gravel, dirt, clay and the like 25 metal bearing earths.

One of the main objects of the invention is the provision of an improved method of extracting and separating metals from metal bearing earths with which they are 30 mixed and present in the free state, so as to permit of extracting and separating a maximum proportion of the metal present in such earths with the resulting reduction in loss and waste, irrespective of the varying forms in which the metal may be encountered.

Another of the main objects of the invention is to provide simple, efficient apparatus for carrying out and performing the extraction and separation of metals in the free state from metal bearing earths, in accordance with the method of the invention.

With the foregoing and various other objects and results in view, which other objects and results will be readily apparent to those familiar with this art from the following explanation, the invention consists in certain novel features, and in certain novel constructions and arrangements and combinations of elements, as will be more

fully and particularly referred to and specified hereinafter.

The accompanying drawing is a more or less diagrammatical view in vertical section with parts in side elevation, of a machine for extracting and separating metals in the free state from metal bearing earths, in accordance with the invention.

In the accompanying drawing a machine or apparatus is disclosed for extracting and separating gold by the method of the invention, from earths in which the gold is present in a free state, although it is to be understood as will be apparent, that the method or apparatus of the invention are not limited to the separation of gold, but are also adapted to the extraction and separation of metals generally from those earths in which the metals are present in a free state. The apparatus presented here- 60 with is merely disclosed as an example of one possible means of carrying out the invention, and the method is described in connection with the separation of gold for purposes of explanation to permit of bringing forth the objects and results of the method of the invention for separating metals from the earths in which they are present.

Gold in the free state is found mixed with earths, such as dirt, gravel, clay or the like and combinations thereof, in particles of varying sizes ranging from nuggets or particles of relatively large size to grains or flakes of exceedingly small size, and the problem encountered consists in extracting 65 and separating these various sizes and forms of metal, such as gold, with a minimum of loss or waste, and the separation and reclaiming of a maximum of the metal present in the earth with which it is mixed. 70

According to the method of the invention the gold or other metal bearing earth is placed in and moistened with a suitable amount of water and the largest particles forming the earth such as stones, gravel 75 and the like, including any large particles or nuggets of gold are separated and washed out from the mass of earth and water. The remaining mass of earth is then subjected to a further separation by which particles 80 of a smaller size including gold particles are separated and washed out leaving the remaining mass formed of very fine particles or grains and flakes of earth and gold. This resultant mass of fine particles of earth 85

2
and metal with water is finally subjected to centrifugal action which throws the very fine flakes of metal to the outer portion of the mass against a mercury coated surface 5 which collects these fine flakes of gold by amalgamation. The coarser particles of gold in the mass of earth and water subjected to centrifugal action pass by gravity to the bottom of the mass into a collecting 10 bowl or pan having a body of mercury therein which extracts and separates such particles by amalgamation therewith. The particles of gold collected by amalgamation on the mercury coated surface and in the 15 mercury bowl or pan can be removed and reclaimed in any of the well known manners familiar to those skilled in this art, while the particles of gold or nuggets separated and washed out from the mass with 20 the particles of earth prior to the extraction by amalgamation of the very fine particles, are separated and reclaimed in any desired manner. By the foregoing method it is 25 possible to secure a maximum proportion of gold from the earth with which mixed, as the very fine grains or flakes of gold are readily extracted by amalgamation and are not lost or wasted, due to the subjecting of the earth and water mass to centrifugal ac- 30 tion which forces the finer particles into contact with the mercury coated surface, while the heavier particles not acted upon by centrifugal force are permitted to drop through the mass by gravity into the mer- 35 cury of a collecting pan or bowl.

In the accompanying drawing one possible form of apparatus or machine for carrying out the foregoing method is disclosed. In this form of apparatus of the invention 40 a metal cylinder or the like 6 is mounted in a vertically disposed position on any suitable or desired base or frame (not shown) by the supporting brackets 21 formed in the present instance of angle 45 iron. A screen 9 is mounted at the upper portion of the iron cylinder 6 a distance below the upper end thereof, upon the brackets 11 which are secured to the hangers 7 suspended from the upper edge of the cylinder 6. A bracing member 10 is provided around the outer edge portion of the screen 9 on the under surface thereof to stiffen and strengthen the screen. The screen 9 is 50 formed with apertures therethrough of a size to separate from the metal bearing earth the largest particles thereof, such as rocks and large gravel, while permitting the fine gravel, sand and such like to pass therethrough.

60 A second screen 13 is mounted in the cylinder 6 a distance inwardly from and below the upper screen 9 on supporting brackets 11 secured to the hangers 7, in a manner similar to the mounting of the screen 9. 65 The screen 13 is provided with the bracing

member or ring 14 secured around the under side thereof at the outer or rim portion to stiffen and strengthen the screen in operation and use. The apertures of the screen 13 are smaller in size than those of screen 70 9, and separate the fine gravel and larger particles of the metal from the sand and fine particles of metal, permitting these latter to pass therethrough.

An operating shaft 5 is mounted in a vertical position extending axially through the cylinder 6 and centrally through the separating screens 9 and 13. The shaft 5 is supported at its upper outer end portion in a bearing bracket 1 of the usual or any other desired type, and has a pinion 4 fixed thereon for rotation therewith. A driving shaft 3 operatively connected with any suitable or desired source of power (not shown) is provided with a bevel gear 2 in mesh with the pinion 4 on the operating shaft 5, so that the latter is rotated upon operation of the driving shaft 3, as will be clear by reference to the accompanying drawing. Blades 8 are mounted extending radially from a hub 33 fixed on the shaft 5, so as to extend across the upper surface of the screen 9 in substantial sliding engagement therewith, and similar blades 12 are mounted extending radially from a hub 34 fixed on the shaft 5, so that the blades 12 extend across the upper surface of the screen 13 in sliding engagement therewith. The mounting and position of the blades 8 and 12, is such that they are revolved across the upper surfaces 90 of the screens 9 and 13, respectively, upon rotation of the shaft 5 by the driving shaft 3 and meshed gear 2 and pinion 4. An opening controlled by a sluice gate 15 is provided through the cylinder 6 adjacent 105 and above the screen 9, and a similar opening controlled by a sluice gate 16 is provided in the cylinder 6 adjacent and above the screen 13. By means of these sluice gates 15 and 16 the materials separated by 110 the screens 9 and 13, respectively, are forced through the respective openings by the revolving blades 8 and 12.

The lower end of the cylinder 6 is outwardly flanged and a bottom or closure plate 26 is removably fixed over and closing the open lower end of the cylinder 6 by means of the clamps 28 fitting over the flanged lower end of the cylinder. A cylinder 17 formed in the present instance of copper, 120 although the invention is not so limited, as any other material having the necessary characteristics to secure the required results may be utilized, is mounted within and concentric with the portion of the iron cylinder or casing 6 below the separating screen 13 with the operating shaft 5 extending axially therethrough. The cylinder 17 may be mounted and supported in position in any suitable or desired manner, as for example 125 130

by the supports 35 shown in the accompanying drawings, with the lower end of the cylinder 17 terminating above and spaced from the bottom plate 26. The inner surface of the copper cylinder 17 is coated with quick silver or mercury to form a gold collecting surface by amalgamation of the small particles of gold when forced into contact therewith, as will be explained more fully hereinafter. It is to be noted at this point that while a copper surface coated with mercury is employed in the present instance for collecting the fine particles of gold, various other materials may be employed to form collecting surfaces suitable to the conditions and characteristics of the metals to be extracted and separated.

A sleeve or hub 20 is mounted on the shaft 5 within the mercury coated cylinder 17 and is provided with a series of paddles or blades 18 extending radially therefrom for rotation within the cylinder 17 by the shaft 5. The pitch and mounting of the blades 18 on the shaft 5 in cylinder 17 is such that when rotated within a body of liquid in the cylinder a whirling of the liquid is set up and particles of matter in suspension therein are forced outwardly through the liquid into contact with the inner surface of the cylinder by the action of centrifugal force. Any suitable or desired bearing 36 is positioned at the lower end of and receiving the shaft 5. At the extreme lower end of the shaft 5 the blades 22 are mounted on a hub 37 for rotation by the shaft and these blades 20 are disposed extending radially from the shaft in opposite directions spaced a distance below but in proximity to the lower end of the collecting and amalgamating cylinder 17. A water or liquid discharge port or outlet 24 is formed through a wall of the cylinder or casing 6 at the lower end of the cylinder 17 substantially in line with but extending a distance above the path of rotation of the blades 22, and a second discharge port or outlet 23 is provided disposed above the outlet 24 at the upper portion of the cylinder 17. The purpose and functions of the discharge ports or outlets 23 and 24 will be explained in detail hereinafter.

A shaker pan 25 is disposed within the cylinder or casing 6 spaced from the lower end of the collecting and amalgamating cylinder 17 below the blades 22 and on the bottom plate or closure 26. The shaker pan 25 is mounted on and fixed to a vertically disposed shaft 29 extending upwardly through the bottom plate 26 in a bearing 27 on the under side thereof. The shaft 29 is formed with an arm 30 extending laterally therefrom in which a lever 31 is pivotally mounted. The lever 31 extends to and is pivotally mounted at its opposite end on and to a crank disk 32 which is rotated by a shaft suitably connected to a source of power (not

shown) in any desired manner. Thus, by rotation of crank disk 32 the lever 31 is reciprocated and rocks or rotates the shaft 29 back and forth to actuate the shaker pan 25, as will be clear from the drawing. In order to steady the shaker pan 25, the upper end of shaft 29 is provided with a pin 38 which loosely fits upwardly into a bore in the end of the operating shaft 5, axially aligned therewith. The bottom of the shaker pan 25 is filled with mercury for amalgamation with and extraction of the coarse particles of metal which pass downwardly through the cylinder 17 by gravity.

In operation and use, the metal bearing earth, in the present instance earth having gold in the free state mixed therein, is poured together with water into the open upper end of the cylinder or casing 6 onto the screen 9, and the operating shaft 5 is rotated by the driving shaft 3. The blades 8 on the screen 9 are revolved thereover by shaft 5 and the gold bearing earth is forced through the screen 9, with the exception of the large particles such as rocks, large gravel and the like; which are separated from the mass of earth and water by the screen. The sluice gate 15 is opened and the separated rocks, gravel, etc. are forced outwardly therethrough by the revolving blades 8. The resultant mass of gold bearing earth drops from screen 9 onto the screen 13 and the blades 12 revolving thereover force the sand and grains and flakes of gold through the screen 12, which separates out the gravel and nuggets of gold. The material separated by the screen 13 is forced outwardly through the sluice gate 16, which is opened and is then collected and the gold nuggets or particles are separated from the gravel and such in any usual or desired manner well known to those familiar with this art.

The water poured into the cylinder or casing 6 fills the lower portion thereof and forms a body or mass with the sand and fine grains and flakes of gold which pass through the screen 13 into the cylinder 17. The blades 18 rotating in this mass force the fine particles or light flakes of gold outwardly into contact with the cylinder 17, with the result that these particles of gold amalgamate with the mercury coated surface of the cylinder and are thus extracted and separated from the mass of earth and water. The heavier particles or grains of gold which are not thrown into contact with the mercury coated surface of the cylinder 17, drop by gravity into the shaker pan 25 and are extracted and separated from the mass of water, sand and fine particles of earth by amalgamation with the mercury in the shaker pan. The blades 22 revolving in the mass of water agitate the sand and earth particles and force them outwardly through

the water outlet 24, which with outlet 23 permits passage of the water from the apparatus. In order to obtain the gold extracted and separated by the amalgamation 5 steps of the method, the clamps 28 are removed and the bottom plate 26 taken off, the shaker pan assembly and cylinder 17 are then withdrawn from the cylinder or casing 6 and the amalgamated gold taken 10 from the shaker pan and the inner surface of cylinder 17. Thus, in the foregoing manner by means of the method and apparatus of the invention the maximum of gold is extracted from the earth, due particularly 15 to the amalgamation steps which collect the fine gold particles such as the flakes and grains with a minimum of loss.

It will be evident that various changes, modifications, variations and substitutions 20 might be resorted to without departing from the spirit and scope of the invention and hence it is not desired or intended to limit the invention to the exact disclosure hereof.

Desiring to protect my invention in the 25 broadest manner legally possible, what I claim is:

1. In a machine for extracting and separating metals in the free state from metal bearing earths, a series of separating screens 30 adapted to separate out the larger particles of earth and metal from earth forced therethrough, means embodying blades movable over said screens for forcing earth therethrough and for removing the separated 35 particles therefrom, and means for extracting and separating the fine grains and particles of metal by amalgamation from the residue of earth after passage through said screens.

40 2. In a machine for extracting and separating metals in the free state from metal bearing earths, a series of separating screens adapted to separate out the larger particles of earth and metal from earth forced 45 therethrough with a body of water, means embodying scraper blades movable over said screens for forcing earth and water therethrough and for removing the separated particles, means for collecting the water and 50 residue of metal bearing earth after passage through said screens, and means for extracting and collecting the fine particles of metal from the mass of earth and water after passage through said screens, by amalgamation.

55 3. In a machine for extracting and separating metals in the free state from metal bearing earths, a series of separating screens for separating the larger particles of metal and earth when forced therethrough with 60 water, means for forcing the earth through said screens, means for collecting the fine particles of metal in the residue of earth by amalgamation after passage through said 65 screens, and means for forcing the fine par-

ticles of metal in the residue mass of earth and water outwardly therethrough into contact with the amalgamating means by centrifugal force.

4. In a machine for extracting and separating metals in the free state from metal bearing earths, a casing, a series of separating screens mounted therein and thereacross, an amalgamating surface in said casing below said screens, means for forcing 70 metal bearing earth and water through said separating screens, and means for forcing the fine particles of metal in the earth residue after passage through said screens into contact with said amalgamating surface. 80

5. In a machine for extracting and separating metals in the free state from metal bearing earths, a casing, a series of separating screens mounted therein, a bottom closure for said casing to form a chamber 85 therewith below the separating screens, an amalgamating surface in the casing below said screens, means for forcing metal bearing earth through said screens with a body of water, the chamber formed in the casing below said screens receiving the earth residue and water, and means for forcing the fine particles of metal in the earth residue through the mass in said chamber into contact with said amalgamating surface for 90 collection thereby.

6. In a machine for extracting and separating metals in the free state from metal bearing earths, a casing, a series of separating screens mounted therein, a bottom closure for said casing and forming a chamber therewith below said screens, an amalgamating surface mounted in the chamber formed by said closure, means for forcing 100 metal bearing earth and water through said screens to separate the larger particles of earth and metal from the mass, the chamber in said casing receiving the earth residue and water after passage through said 105 screens, and blades mounted in said chamber for rotation through the mass of earth residue and water to force the small particles of metal in the residue into contact with the amalgamating surface by centrifugal action. 110

7. In a machine for extracting and separating metals in the free state from metal bearing earths, a casing, a series of separating screens mounted therein, a chamber formed in said casing below said screens, an amalgamating shaker pan mounted in the lower portion of said chamber, an amalgamating surface mounted in said chamber above the shaker pan, means for forcing metal bearing earth and a body of water through said screens, the residue of earth and the water forming a mass within said casing chamber after passage through the screens, and means within said chamber for forcing the lighter particles of metal in the 115 120 125 130

earth residue through the mass by centrifugal action into contact with said amalgamating surface, the heavier particles of metal in the residue passing by gravity into 5 and collected by said shaker pan.

8. In a machine for extracting and separating metals in the free state from metal bearing earths, means for separating out the larger particles of earth and metal, a 10 chamber for receiving the earth residue after separation of the larger particles for suspension in a body of water in the chamber, an amalgamating pan in said chamber, means for oscillating said pan, an amalgamating surface in said chamber above 15 said pan, and means for setting up centrifugal action in the mass of earth residue and water in the chamber to force the lighter particles of metal therein through the mass 20 into contact with said amalgamating surface and to permit the heavier metal particles to drop by gravity into said amalgamating pan.

9. In the art of extracting and separating 25 metals in the free state from metal bearing earths, those steps which consist in placing metal bearing earth in a body of water, subjecting the water and earth residue to centrifugal action to force the lighter metal 30 particles outwardly through the mass into contact with an amalgamating surface while permitting the heavier metal particles to drop downwardly through the mass by gravity, and collecting the heavier particles of 35 metal on an amalgamating surface while agitating said surface.

10. In the art of extracting and separating metals in the free state from metal bearing earths, those steps which consist in progressively separating out the larger particles of earth and metal from a mass of earth, the largest sizes first and smaller sizes next, placing the earth residue in a body of water, subjecting the mass of earth and water to 40 centrifugal action to force the lighter particles of metal laterally through the mass into contact with a fixed amalgamating surface surrounding the mass while permitting the heavier particles of metal to drop downwardly through the mass by gravity, and then collecting the heavier particles so separated.

11. In the art of extracting and separating 45 metals in the free state from metal bearing earths, those steps which consist in forming a mass of water and metal bearing earth within a fixed amalgamating surface laterally surrounding the mass, subjecting the mass to centrifugal action to force the lighter particles of metal laterally through the mass into contact with the surrounding amalgamating surface while permitting the heavier metal particles to drop by gravity 50 through the mass, and collecting the heavier particles of metal so separated on an amalgamating

surface below the mass of earth and water within the fixed amalgamating surface.

12. In a machine for extracting and separating metals in the free state from metal 70 bearing earths, a casing, a series of separating screens mounted therein, a removable bottom closure for said casing forming a chamber therein below said screens, an amalgamating surface mounted in the chamber 75 formed by said closure, and a shaker pan mounted on said closure within the casing and removable therewith.

13. In a machine for extracting and separating metals in the free state from metal 80 bearing earths, a casing, a series of separating screens in the upper portion of said casing, a removable bottom closure for said casing forming a chamber therewithin below said screens, a vertically disposed amalgamating surface removably mounted in 85 said chamber, and a horizontally disposed amalgamating surface mounted on and removable with said end closure.

14. In a machine for extracting and separating metals in the free state from metal bearing earths, a casing, a removable bottom closure for said casing forming a chamber therewithin, a vertically disposed amalgamating surface removably mounted in 90 said chamber spaced from the casing wall, and a horizontally disposed amalgamating surface mounted on said bottom closure within the chamber below said vertically disposed surface, the said horizontally disposed amalgamating surface removable with 95 said bottom closure.

15. In a machine for extracting and separating metals in the free state from metal bearing earths, the combination with a vertically disposed amalgamating surface, of a horizontally disposed amalgamating shaker pan mounted below and spaced from said 100 vertically disposed surface.

16. In a machine for extracting and separating metals in the free state from metal bearing earths, the combination with a vertically disposed substantially cylindrical open end amalgamating surface, of a horizontally disposed amalgamating shaker pan mounted below and extending across the lower open end of said vertically disposed 110 surface.

17. In a machine for extracting and separating metals in the free state from metal bearing earths, a casing, a removable bottom closure for said casing forming a chamber therewithin, a substantially cylindrical open end amalgamating surface 120 mounted on said removable closure and vertically disposed within the casing above said closure and spaced from the casing wall, an amalgamating shaker pan mounted on said closure within the casing below said vertically disposed surface, and said shaker pan 125 130

and vertically disposed amalgamating surface removable from said casing with the said bottom closure.

18. In a machine for extracting and separating metals in the free state from metal bearing earths, a casing, a series of separating screens mounted in the upper portion of said casing, means for forcing earth and water through said screens, a bottom closure for said casing forming a chamber therewithin below said screens, a vertically disposed amalgamating surface in said chamber below said screens and spaced from said bottom closure, a series of blades rotatably mounted in said casing chamber for subjecting a mass of earth and water therein to centrifugal action, an amalgamating shaker pan mounted in said chamber below said vertically disposed surface, means for oscillating said shaker pan, and the said casing and vertically disposed surface formed with discharge ports therethrough from the chamber therein below said separating screens.
19. In a machine for extracting and separating metals from metal bearing earths, a casing, a series of separating screens mounted in the upper portion of said casing, means embodying blades movable over said screens for forcing earth and water through said screens, a bottom closure for said casing forming a chamber therewithin below said screens, a vertically disposed amalgamating surface in and extending around said chamber below said screens, a series of blades rotatably mounted in said casing chamber and surrounded by said amalgamating surface for subjecting a mass of earth and water therein to centrifugal action.

mating surface for subjecting a mass of water and earth therein to centrifugal action, an amalgamating shaker pan mounted in said chamber at the lower end of said vertically disposed amalgamating surface, the said casing formed with a discharge port therethrough from the chamber formed therein below said separating screens, and means causing circulation of the mass in said chamber outwardly therefrom through the casing discharge port.

20. In a machine for extracting and separating metals from metal bearing earths, the combination with a vertically disposed substantially annular amalgamating surface, of a horizontally disposed amalgamating surface mounted at the lower end of said vertically disposed surface, and means disposed within and surrounded by said vertically disposed surface for subjecting a mass therewithin to centrifugal action.

21. In a machine for extracting and separating metals from metal bearing earths, the combination with a vertically disposed substantially annular amalgamating surface, of an amalgamating shaker pan mounted beneath said vertically disposed surface, means for vibrating said pan and blades rotatably mounted within and surrounded by said vertically disposed surface above said shaker pan for subjecting a mass within said vertically disposed surface to centrifugal action.

Signed at Ithaca, New York, this 10th day of September, 1923.

ALBERT KOCH
